UNITED STATES PATENT OFFICE

WILLIAM H. BENDRY, OF HANCOCK, MICHIGAN

ROTARY ENGINE

Application filed October 6, 1924. Serial No. 742,055.

This invention relates to engines of the rotary type and the primary object of the invention is to provide a steam engine of exceptionally simple and durable construction, 5 which will permit the greatest amount of energy to be obtained from the steam.

Another object of the invention is to provide an improved steam engine which can be readily and quickly reversed without un- 10 due loss of steam.

A further object of the invention is to provide novel means for operating the control valve from the engine rotor for permitting the passage of the vanes past said valve without 15 injury thereto.

A further object of the invention is the provision of novel means for controlling the exhaust valves of the engine according to the direction of rotation of the rotor of the engine. 20

A still further object of the invention is to provide an improved engine of the above character which will be efficient in use, one that will be simple and easy to manufacture 25 and one which can be placed upon the market at a reasonable cost.

With these and other objects in view, the invention consists in the novel construction, arrangement and formation of parts, as will 30 be hereinafter more specifically described, claimed, and illustrated in the accompanying drawings, in which drawings,

Figure 1 is a front elevation of the improved engine,

Figure 2 is a top plan view of the same,

Figure 3 is a longitudinal section through the engine showing the arrangement of the rotor within the casing or stator.

Figure 4 is a vertical longitudinal section 40 through the engine showing the rotor removed therefrom.

Referring to the drawings in detail, wherein similar reference characters designate corresponding parts throughout the several views the letter A generally indicates the improved engine which comprises a stator B and rotor C.

The stator B includes an annular outer wall 10 having the right angularly disposed 50 flanges 11 formed on its peripheral edges to

which are adapted to be bolted the disk shaped end plates 12 and 13 of the said stator. These disk shaped end plates 12 and 13 are provided at the axial centers thereof with suitable bearings for rotatably supporting 55 the drive shaft 14 to which is keyed or otherwise secured the rotor C, which will be hereinafter more fully described. The outer annular wall 10 of the stator has formed transversely thereof a substantially semi-cylindrical housing 15 which in turn has formed longitudinally thereof a semi-cylindrical steam chest 16 into which the live steam is adapted to flow from a steam pipe 17 which may lead from any suitable source of supply. 60

A rotary valve 19 of cylindrical formation is mounted within the steam chest 16 and is provided with semi-circular steam way 20 for permitting the flow of steam from 70 the steam chest into the semi-cylindrical housing 15.

Rockably mounted within the semi-cylindrical housing 15 is a substantially solid semi-cylindrical abutment 21 which has its curved 75 face 21^b normally in engagement with the outer face of the valve 19, and arranged to form one wall of the steam passage 21^c of the housing 15.

It can be seen that the abutment 21 is 80 adapted to be rocked for bringing one edge or the other into intimate engagement with the periphery of the rotor C as will be hereinafter more fully described. As shown in Figure 3 of the drawing the valve 19 and the 85 abutment 21 is arranged to permit the steam to flow into the stator or casing at the right hand side thereof which will bring about the clockwise rotation of the rotor.

The outer wall 10 of the stator on each side 90 of the semi-cylindrical abutment housing 15 is provided with manually controlled relief valves 22 and 23 for permitting the escape of pressure from the engine when so desired or necessary. The opposite side of the stator 95 from the abutment casing 15 is provided with transversely extending escape or exhaust chambers 24 and 25 and it can be seen that these chambers are located on opposite side 100 of the vertical diametric center of the tur-

bine. These exhaust chambers 24 and 25 are connected together by a circumferentially extending pipe 26 and this pipe has connected thereto an outlet pipe 27 by means of which the steam can escape to the atmosphere. 5 Suitable control valves 28 and 29 are mounted within the chambers 24 and 25 for controlling the flow of exhaust steam into the same and these valves 28 and 29 are mounted on shafts 30 which extend through the end wall 10 15 of the stator. It is to be also noted at this time that the valve 19 and the abutment 21 are provided respectfully with stems 31 and 32 for a purpose which will be hereinafter more fully described.

The rotor C comprises an annular relatively thick rim 35 and a solid disk shaped hub 36 which can be provided at spaced points with openings 37 for lessening the weight thereof. 20 The hub plate 36 is of course keyed or otherwise secured to the shaft 14. The rotor C can be provided with any desired number of vanes and as clearly shown in Figure 3 of the drawing I have provided a pair of vanes 38 which are disposed at diametrically opposed points on the rotor. These vanes extend radially from the rim of the rotor and are preferably of a wedge shape and are slidably fitted in grooves 29 formed transversely in the rim 25 of the rotor. By this construction it can be seen that the vanes can be readily slipped into position on the rotor. Of course however when the rotor is in place, displacement of the vanes is absolutely precluded in view of 30 the fact that the same are engaged by the end plates 12 and 13 of the stator. The outer face of each vane is provided with friction pads 50 for engaging the inner periphery or face of the outer wall 10 thereby effectively 35 preventing the escape of the motive fluid past the same and the stator.

One end of the drive shaft 14 has secured thereto in any desired way an indicator wheel 40 which is provided at diametrically opposed points with fingers 41. These fingers 41 are in direct alignment with the rotor vanes and are provided for indicating the position 45 of the vanes in the stator, when it is desired to reverse the operation of the rotor. Rigidly 50 secured to the controller valve 21, that is to say to shaft 32 thereof, is a substantially semi-circular head plate 42 which in turn carries a bearing rib 43 radially arranged with respect to the shaft 32. A lever 44 is rockably 55 mounted on the shaft 32 at a point intermediate its ends and the lever on opposite sides of a bearing plate 43 carries a leaf spring 45 for engaging the opposite sides of the said bearing rib. The lever 44 is held in any preferred adjusted position by means of a dog 60 and a sector rack bar 46. The lever 44 directly below the head plate 42 carries a depending indicating arm 47' which in connection 65 with the fingers 41 on the wheel 40 clearly

indicates the position of the abutment 21 and the vanes.

Now it is to be noted when the vane 38 passes the abutment 21 that the abutment will rock against the tension of the spring 45 and the spring will quickly return the abutment to its normal position in engagement with the periphery of the rotor.

It can be seen that by moving the lever 44 the position of the abutment 21 can be 75 changed to permit the reversing of the rotor.

In order to bring about the reversing of the rotor C, when so desired, a manually operated lever 47 is secured to the stem 31 and of course when the position of the abutment 21 is changed, the position of the valve 19 is 80 changed therewith. The hand lever 47 can be locked in any desired position by any suitable means such as a pawl and ratchet.

In order to bring about the synchronous 85 operation of the exhaust valves 28 and 29 the shafts thereof have secured thereto slotted crank arms 60 to which are slidably and pivotally connected links 61. These links 61 are in turn pivotally connected to a manually 90 operated lever 62 which is pivotally mounted upon the stator. Now by shifting this lever either one of the exhaust valves can be opened or closed as is desired.

In use of the improved engine, when the 95 controller and inlet valves are arranged as shown in Figure 3 of the drawing, the steam will enter the steam chest 16 through the pipe 17 and flow around the channel ways 20 in the inlet valve past the abutment 21 to the right hand side of the vertical center of an engine 100 and impinge against the vanes moving the rotor in a clockwise direction. As stated as each vane passes the abutment the same is automatically lifted to prevent injury to the 105 vane and the abutment.

When it is desired to reverse rotation of the engine it is merely necessary to operate the 110 manually controlled levers 44, 47 and 62 which will change the position of the valve 19 and abutment 21 and permit the steam or other motive fluid to flow into the left hand side of the engine. The lever 62 should then also be rocked to close the exhaust valve 29 and open the exhaust valve 28.

Changes as in detail may be made without departing from the spirit or the scope of this invention, but what I claim as new is:—

1. A rotary engine comprising a cylindrical stator, a semi-cylindrical housing extending outwardly from and transversely of the annular wall of the stator, the inner side of the housing being fully open and in full communication with the stator, a semi-cylindrical steam chest extending outwardly from and longitudinally of the housing and having an inlet, the inner side of the steam chest being fully open and in full communication with the housing, a rotor arranged within the stator and provided with vanes, a solid 125

semi-cylindrical abutment rotatably supported within the housing with its curved wall in spaced relation to the corresponding wall of the housing to provide a passage from the steam chest to the stator, the abutment contacting at one end with the rotor, a cylindrical valve rockably supported within the steam chest in contact with the curved wall of the abutment and the corresponding wall of the steam chest, the valve extending across the passage between the abutment and housing and provided with a semi-circular steam passage communicating with the inlet of the steam chest, means for adjusting the abutment and yieldingly holding it in adjusted position, and means for adjusting the valve.

2. A rotary engine comprising a stator, a rotor, an abutment arranged within the stator, a shaft rockably supporting the abutment, a plate fixedly secured to the shaft outwardly of the stator, a rib on the plate and arranged radially with respect to the shaft, a lever rockably supported on the outer end of the shaft and extending in opposite directions beyond the rib, means for holding the lever against accidental movement, and leaf springs each fixedly secured at one end to the lever at opposite sides of the rib and having the free ends thereof bearing against said sides of the rib.

In testimony whereof I affix my signature.
WILLIAM H. BENDRY.
